US0D1020884S

(12) **United States Design Patent** (10) **Patent No.:** **US D1,020,884 S**
(45) **Date of Patent:** **** Apr. 2, 2024**

(54) **PEN HOLDER**

(71) Applicant: **Jian Wang**, Hongjiang (CN)

(72) Inventor: **Jian Wang**, Hongjiang (CN)

(**) Term: **15 Years**

(21) Appl. No.: **29/842,026**

(22) Filed: **Jun. 9, 2022**

(51) LOC (14) Cl. **19-06**

(52) U.S. Cl.

USPC **D19/202**; D19/99

(58) **Field of Classification Search**

USPC D19/37, 38, 65, 99, 100, 202; D15/138, D15/140

CPC B23K 9/26; B23K 9/013; B23K 9/164; B08B 5/02
